UNITED STATES PATENT OFFICE

2,127,114

TWO-STROKE INTERNAL COMBUSTION ENGINE

Wilhelm Grab, Freiburg in Baden, Germany

Application April 19, 1937, Serial No. 137,774
In Germany April 24, 1936

2 Claims. (Cl. 123—59)

The object of the invention is a two-stroke combustion engine with working cylinders which are alternately charged by a feed pump, in such a manner that the combustible charge supplied to the working cylinders by the feed pump piston is always equal with respect to volume, provided that the pressure is held constant to the stroke volume of the working cylinder; whereas this charge is introduced in a known manner from 5 the top into the working cylinder head, in such a manner that the entering current of gas mixture is caused to follow a progressive movement of helical direction from the top downwards, so as to secure a perfect scavenging of the working 10 cylinders. By means of this structure, in view of the known constructions, a larger output per volume stroke will be obtained, so that for equal output, smaller dimensions and a reduced weight of the machine may be secured.

In the drawings a two-stroke engine is illustrated with two working cylinders, given by way 15 of example and in accordance with the invention, the drawings comprising five figures.

Fig. 1 is a longitudinal section of the engine 20 through the two working cylinders and the feed pump;

Fig. 2 is a side elevation of the feed pump in longitudinal section;

Fig. 3 illustrates the inlet port for the fresh 30 gas mixture as seen from below;

Fig. 4 is a section through the inlet port for the mixture on line A—B—C of Fig. 1;

Fig. 5 is a section through the head of a working cylinder on line D—E of Fig. 1.

In both working cylinders 1 and 2, the two working pistons 3 and 4, which are displaced 180°, act on the crank-shaft 5. The charge is introduced in the working cylinders each time from the top into the cylinder head at 6 and 7, and at 35 this inlet, the entering mixture is caused to flow along a helical sloping face starting from the top at the inlet port and directed downwards. As may be seen in Fig. 3, it may be observed that, on the one hand, the charge is more readily introduced into the working cylinder, while, on the other hand, a progressive helical movement is imparted to the mixture, so that thereby a rapid and perfect scavenging is secured, by the fact that the remaining spent gases from the last 40 working stroke will be caught by this turbulent movement to be expelled downwards, through the exhaust slits 8 and 9 provided in the working cylinders at the end of the stroke.

Between the two working cylinders 1 and 2 is 45 arranged the feed pump 10, the piston 11 of which

is actuated by the crank 12. In the form of embodiment illustrated in the drawings, the proportions are so selected that the crank-shaft 12, driven by the pair of gears 13, 14, rotates at twice the speed of the working crank-shaft 5, that its stroke, however, is only one half of the stroke of the working pistons 3 and 4, that the piston diameter is twice the diameter of the working pistons, so that, in this way, the feed pump supplying alternately the working cylinders delivers 5 at each time to a working cylinder a charge corresponding to the working volume, the same pressure being provided in the feed pump and the working cylinder.

The distribution of the feed pump is controlled 10 by the sleeve valve 15, which is driven by the working crank-shaft 5, by means of the forked connecting rod 16. At 17 is connected the tubular conduit starting from the carburettor and from where the mixture is sucked through the 15 inlet port 18 of the sleeve valve into the charging room above the piston 11 of the feed pump 10. The gas mixture penetrates alternately through the outlets 19, in the inlet channel 20 of the cylinder 1 and the inlet channel 21 of the cylinder 2, both inlet channels conducting through the 20 ports 6 and 7.

The speeds of the working piston and of the supply piston are the same, as the reciprocating movement of the supply piston is as a whole equal 25 to the single stroke of the working piston. For each stroke of the working piston, the supply piston operates a suction stroke and a compression stroke. The sleeve valve has half the stroke of the working piston and half the speed of the 30 supply piston. The adjustment of the feed pump with respect to the working cylinders is such that, when the working cylinder pistons have opened the exhaust slit for half the height during the 35 downward movement, the supply of fresh gas mixture by the feed pump is started in the working cylinder, as it is illustrated in Fig. 1. The working piston, in its further downward movement, completely frees the exhaust slits until the stroke end and starts closing the same again slowly when 40 its upward movement begins. As soon as the exhaust ports are closed, the feed pump, in accordance with the selected dimensions cited by way of example, has pressed in the cylinders 3/4 of the stroke volume of the said cylinders, which 45 corresponds with the working cylinder volume from the upper edge of the exhaust ports to the start of the stroke from above. The remaining stroke of 25% of the feed pump piston corresponds to the volume content of the part of the 50 55

backward stroke made by the working piston from the starting end of the stroke from below. During the last fourth part of the movement of the supply piston, said feed pump will act as a compressor, which supplies to the working cylinder, under pressure, a gas volume corresponding to the height of the exhaust ports. This auxiliary charge prevents the loss of volume in the working cylinders, which may be observed in known constructions of combustion motors having exhaust ports in the working cylinders, said loss corresponding to the height of the exhaust ports.

I claim:

1. In a two-stroke internal combustion engine comprising two working cylinders, working pistons therein, piston rods and a common crank-shaft, an inlet port in each working cylinder close to the cylinder head, exhaust ports in the cylinder walls, a pump cylinder located between and in alignment with the working cylinders, a pump piston therein, an auxiliary crank-shaft connected to said pump piston, a two to one ratio driving gear between both crank-shafts, an inlet port in the pump cylinder, oppositely arranged outlet ports in the pump cylinder forming direct communications with the inlet ports of the working cylinders respectively, a sleeve-valve located between the pump cylinder and its piston, and an eccentric driving connection between the common crank-shaft and the sleeve-valve for controlling the supply of gas mixture to the work-

ing cylinders through said outlet and inlet ports.

2. In a two-stroke internal combustion engine comprising two working cylinders, working pistons therein, piston rods and a common crank-shaft, an inlet port in each working cylinder close to the cylinder head, an inner helical slope extending tangentially from the inlet port inside the working cylinder, exhaust ports in the cylinder walls, a pump cylinder located between and in alignment with the working cylinders, a pump piston therein, an auxiliary crank-shaft connected to said pump piston, a two to one ratio driving gear between both crank-shafts, an inlet port in the pump cylinder, oppositely arranged outlet ports in the pump cylinder forming direct communications with the inlet ports of the working cylinders respectively, a sleeve-valve located between the pump cylinder and its piston, and an eccentric driving connection between the common crank-shaft and the sleeve-valve for controlling the supply of gas mixture to the working cylinders through said outlet and inlet ports, the arrangement being such that the mixture is supplied to the working cylinders without compression during the main part of the charging stroke of the pump piston, a final supply being made under pressure during the remaining part of said charging stroke which corresponds to that part of the return stroke of the working piston necessary for closing the exhaust ports.

30 WILHELM GRAB.
